George W. Ring & Joshua Crandall, from New York, Letters Patent
No. 200, dated Sept 19th 1848, (assigned to A. Cox & Co.)

The schedule referred to in these Letters Patent and
making parts of the same.

We all, to whom these presents shall come, doth know that
we, Geo. W. Ring and Joshua Crandall, of the City of Troy,
County of Rensselaer, and State of New York, have invented
or produced a new Cooking Stove pattern, the Stoves made
from which are to be called the "Drawing Glass light Cooking
Stove", and we do hereby declare that the drawings marked
Fig. 1, accompanying these specifications are a full
and exact illustration of the same.

What we claim as new and desire to secure by letters patent &
is the production of the new pattern above delineated —
